CLAIM

I claim the ornamental design for an exhaust pipe tip for a vehicle, as shown and described.

DESCRIPTION

FIG. 1 is a bottom view of an exhaust pipe tip for a vehicle; FIG. 2 is a side view of the exhaust pipe tip for a vehicle, the other side view being a mirror image of the side view of FIG. 2;

FIG. 3 is a front view of the exhaust pipe tip for a vehicle.

FIG. 4 is a top view of the exhaust pipe tip for a vehicle.

FIG. 5 is a back view of the exhaust pipe tip for a vehicle.

FIG. 6 is a perspective view of the exhaust pipe tip for a vehicle showing the back; and,

FIG. 7 is a perspective view of the exhaust pipe tip for a vehicle showing the front.

The portion in phantom line and the area circumscribed thereby of the exhaust pipe tip for a vehicle does not form part of the design.
